United States Patent Office.

JOHN F. LITTLE, OF LOCKPORT, NEW YORK.

Letters Patent No. 67,062, dated July 23, 1867.

BARREL-CRESSET.

The Schedule referred to in these Letters Patent and making part of the same.

TO ALL WHOM IT MAY CONCERN:

Be it known that I, JOHN F. LITTLE, of Lockport, in the county of Niagara, and State of New York, have invented a new and useful Improvement in Barrel-Cressets; and I do hereby declare that the following is a full and exact description thereof, reference being had to the accompanying drawing, making part of this specification, and representing a central vertical section of my improved device.

The object of my invention is to provide an apparatus to facilitate the heating process that is necessary in the manufacture of barrels, casks, &c., and it consists essentially of a base-plate, of a removable fire-chamber or cylinder, and also a removable fire-grate, all constructed and arranged as will presently be explained.

As represented in the drawing, A indicates the base-plate of my improved cresset, which is made of an annular form, and of the proper size to conform to that of the barrels which are to be placed thereon. The base-plate is elevated a short distance above the floor or surface on which it rests, and is supported by means of legs b b, secured to the base in any desired manner. On top of the base A is formed a vertically projecting rim, c, extending around near the outer edge of the same, but leaving an extension, d, of the plate outside of the rim, on which the barrel to be heated rests, as represented in red lines. Inside of the outer projecting rim c is also formed a smaller vertical rim or flange, e, which serves as a bearing for the fire-chamber or cylinder B, and over which its end closely fits. Through the base-plate A, within the compass of the flange e, is formed a central opening or draught-passage, g, and across this passage, resting on the shoulder h of the base, is situated a removable grate, l.

When in use the device is preferably situated under a fire-place or chimney, through which the smoke is allowed to pass off, the same as in the ordinary device.

There are several important advantages comprised in this device, which I am not aware were ever before obtained in so cheap and simple a manner. By elevating the base A a little above the surface, a draught of air has a free passage upward through the opening g and fire-chamber, without admitting cold air inside the barrel, the space between it and the fire being closed by the annular plate A, and the heated air is more perfectly confined than is the case in the ordinary device, where only a fire-cylinder is employed, in which case the barrel must be raised slightly in order to admit a draught of air through the fire, when the cold air is admitted inside the barrel and greatly retards the process of heating the same. The rim c not only serves to keep the barrel in position on the base A, but also protects the barrel from becoming burned by coals of fire falling from the base. The grate l is made removable, so as to allow the fire-chamber to be easily cleared from obstructions, and allow the grate to be replaced by a new one when it becomes useless by wear. The fire-cylinder B is preferably formed with numerous perforations or openings in its sides, by means of which a greater degree of radiation is allowed, and the heated air and products of combustion can more readily pass outward into the space between the fire-chamber and sides of the barrel, and thereby greatly facilitates the heating and seasoning process required to equalize the wear of the same, and also to allow the cylinder itself to be replaced by a new one when it becomes worn out. By this arrangement it will be perceived that the base itself will serve for a great length of time, while the grate l and fire-cylinder B can be readily removed, when they become worn or useless, and replaced by new ones.

In the manufacture of this device I prefer making the base A of cast metal, which may be made in a single piece, and substantially of the form represented in the drawing. The fire-cylinder B may be made either of cast or sheet metal, according to the fuel to be used. Where only wood is to be burned it may be made simply of sheet iron, but in the use of coal I prefer the employment of cylinders made of cast iron.

What I claim as my invention, and desire to secure by Letters Patent, is—

The annular base A, in combination with the perforated fire-cylinder B and grate l, constructed, arranged, and operating substantially as and for the purpose set forth.

In witness whereof I have hereunto signed my name in the presence of two subscribing witnesses.
